ATTORNEY.

UNITED STATES PATENT OFFICE.

JOHN STROBEL, OF BURLINGAME, CALIFORNIA.

WRENCH.

Application filed July 11, 1927. Serial No. 204,705

This invention relates to improvements in wrenches. The objects of the invention are, among others, to provide a wrench including a pair of jaws both adjustably mounted on the 5 jaw mounting head and capable of independent adjustment relatively to each other, enabling the offsetting, if desired, of the nut engaged to either side of a line passing longitudinally through the handle should occasion arise which would necessitate the same; to provide a construction wherein the mounting head is of simple construction and formation on each face enabling cheap manufacture, and wherein the jaw members are duplicates 10 of simple construction arranged in reverse pairs when assembled enabling cheap manufacture, the parts adaptable for quick assembling, providing a structure which is adapted for manufacture at little cost; to provide a screw adjustment for each jaw member constructed and arranged in such manner as to enable the wrench user to adjust the respective jaws by thumb and finger movement while the wrench is supported by the same 15 hand. Another and important objects is to provide a handle aperture having tapering walls enabling the reception of nuts of various sizes therein when it is desired to use the handle as a cap wrench, the handle aperture 20 also enabling the insertion of a leverage implement thereinto when axial rotation is desired to be applied to the jaw members when a nut axis is at alignment with the handle.

With the above mentioned and other objects in view, the invention consists in the novel construction and combination of parts hereinafter described, illustrated in the accompanying drawings, and set forth in the claims hereto appended, it being understood 25 that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein:

Fig. 1 is a view in elevation of the preferred embodiment of my invention with the jaws in closed position and meeting on a line extended centrally through the handle.

Fig. 2 is an end view.

Fig. 3 is a view in perspective of one of the jaw plates and its associated jaw.

Fig. 4 is a view in elevation illustrating

the jaws adjusted to a position offset to a line passing centrally through the handle.

In the drawings disclosing the preferred embodiment of my invention, 1 indicates a wrench handle provided with an elongated aperture 2 disposed longitudinally thereof and formed with converging side walls 3. The aperture affords an opening for receiving nuts of various sizes when the handle is used as a cap wrench, also when it is desired to apply leverage to the handle when axial rotation is desired to be applied thereto with the nut axis engaged between the jaws in alignment with the handle. At its opposite end, the handle 1 mounts a head 4 illustrated as an integral part thereof. The end wall of the head is preferably centrally channeled at 5 providing parallel spaced guide flanges 6 one projecting upwardly from each face of the head. At its base, the opposite faces of the head are correspondingly channeled at 7, said channels each comprising in end elevation a horizontal leg 8 and a vertical leg 9 disposed at right angles thereto with the respective legs interconnecting throughout their length 75 and with the horizontal leg opening through the side face of the head. The faces of the head between the channels are formed with transversely disposed arcuate depressions 80 provided with teeth 10 for engagement by the jaw worms hereinafter described. The head 4 mounts a pair of jaw plates 11 from the outer ends of which project the jaws 12, the same being of a thickness when the plates are assembled to overlie the upper edge of the opposing plate as in the drawing and preferably of a width so that their adjacent faces will contact with the outer edges of the respective plates lying flush with the ends of the head. 85 The jaw plates are provided on their inner faces with upper and lower flanges 13 and 14, the upper for reception within the flange 5 and the lower for reception in channel 7. As illustrated, the jaw plates are adapted for assembly on the head 4 by an endwise movement 90 one preferably from each end of the head with the flanges 13 and 14 in their respective channels. Stop members 15 project inwardly into each vertical leg 9 and the channels engage stop lugs 16 and preclude the outward 95 or separating movement of the jaw mounting plates 11. Each plate is provided with an aperture 17 in which is rotatably mounted on an axis 18 a cylindrical barrel 19 having a worm periphery 20, the barrel being of suffi- 100 105 110

cient diameter to enable the worm periphery to project in the worm teeth 10 and to extend beyond the outer face of the jaw plates to facilitate their manipulation.

- 5 As illustrated and described, the jaw plates carrying the respective jaws are independently adjustable relatively to each other and to the jaw plate mounting head enabling the setting of the jaw faces within their limits of 10 adjustment in any desired position relatively to the head to engage the nut desired. Thus the jaw faces may be adjusted to a position wherein both are offset to the same side of line 15 passing centrally through the handle 1, its structure adapting the wrench to uses where offset jaw and handle relation is necessary.

I claim:—

1. A wrench comprising a handle provided with a head formed on its end and in its opposite faces with parallel transversely disposed channels open at their opposite ends and further provided on opposite faces with a threaded worm receiving depression, a pair of duplicate jaw plates formed on one face with parallel transversely disposed flanges and adapted for mounting on the opposite faces of the head from opposite ends with the flanges slidably received within said channels, each of said plates mounting an adjusting worm projecting therethrough and one engaging with the thread of one of said worm receiving depressions, stop means for precluding the relative separating movement of said plates on the head and a jaw projecting beyond the end of each plate and extending laterally from one side of the upper edge of its plate to overlie the upper edge of the other plate when the jaws are assembled.

2. A wrench comprising a handle provided at one end with a jaw mounting head, a pair of duplicate jaw plates having independent interlocking engagement with the opposite faces of the jaw head, each provided with a jaw, said plates mounted on the outer faces of the jaw mounting head and independently movable transversely thereof, an adjusting screw carried by each jaw plate and each having independent threaded engagement with the head whereby said jaws are capable of independent adjustment transversely of the head and to and from each other.

3. A wrench comprising a handle provided at one end with a jaw mounting head, said head provided at its end with an open ended groove affording a pair of parallel flanges projecting beyond the end of the head, and its side faces provided with duplicate open ended guide channels, opposite faces of said head being each further provided with a threaded depression extending the full width of said head and disposed parallel with said channels, a pair of duplicate jaw plates each provided on one face with parallel transverse flanges for slidable interlocking engagement with said end groove, and guide channels, a pair of threaded adjusting screws one projecting through the wall of each jaw plate and each engaging the threaded depression in its associated side wall of said head whereby said jaws are capable of independent adjustment transversely to and from each other, and stop means for precluding the relative outward movement of the jaw plates on the head.

In testimony whereof I have signed my name to this specification.

JOHN STROBEL.
